UNITED STATES PATENT OFFICE.

JOHN H. PLANK, OF BLOOMFIELD, IOWA, ASSIGNOR OF ONE-HALF TO JAMES W. JAGGERS, OF BLOOMFIELD, IOWA.

SHOE-HOLDER.

1,183,766.

Specification of Letters Patent. Patented May 16, 1916.

Application filed August 24, 1915. Serial No. 47,108.

To all whom it may concern:

Be it known that I, JOHN H. PLANK, a citizen of the United States, residing at Bloomfield, in the county of Davis, State of Iowa, have invented certain new and useful Improvements in Shoe-Holders; and I do hereby declare the following to be a full, clear, and exact description of the invention, such as will enable others skilled in the art to which it appertains to make and use the same.

The present invention is directed to improvements in devices for holding shoes when being cleaned or polished, and has for its object to provide a device of this character capable of being easily and quickly adjusted for holding shoes of different sizes.

A further object of the invention is to provide a holder of this character so constructed that the same may be turned to any position desired, either to the right or left.

With these and other objects in view, this invention resides in the novel features of construction, formation, combination and arrangement of parts to be hereinafter more fully described, claimed and illustrated in the accompanying drawing, in which:—

Figure 1 is a perspective view of the device. Fig. 2 is a sectional view on line 2—2 of Fig. 1. Fig. 3 is a sectional view on line 3—3 of Fig. 1. Fig. 4 is a perspective view of the device reversed.

The holder comprises a supporting block 1, which is rotatably secured to the block 1', said block being secured in any suitable manner to a post or wall. The block 1 has its sides provided with a plurality of vertically spaced sockets 2, the purpose of which will appear later. The holder further consists of a horizontal arm 3, which is formed from suitable sheet metal, the rear end of which terminates in a hook 4, said hook being adapted to detachably engage the loop 5 carried by the block 1. The outer end of the arm 3 terminates in a vertically disposed arm 6, said arm having its lower end terminating in a horizontal arm 7 to which the toe block 8 is attached.

The arm 3 is provided upon its upper edge with ratchet teeth 9 and spaced notches 10 the purpose of which will appear later. A lever 11 is provided and is formed with a longitudinal slot 12, said slot being bridged

by pins 13 and 14, the latter being adapted to interchangeably engage the notches 10, 55 while the former has pivotally connected thereto the upper end of the pawl 15, said pawl being adapted to engage the ratchet teeth 9 so as to hold the lever 11 in different adjusted positions. By slotting the lever 11 60 spaced arms 16 are provided, said arms having their lower ends reduced, as at 17 whereby the same may enter the bore 18 of the heel member 19. The heel member 19 is held upon the reduced ends of the arms by 65 a set screw 20. Since the heel member 19 is removably mounted it is obvious that the lever 11 can be easily disengaged from or engaged with the arm 3.

To hold the arm 3 in its operative position a yoke 21 is employed, which is formed from resilient wire, said yoke having its arms 22 terminating in inwardly directed extensions 23 which are adapted to engage selected sockets 2, whereby the yoke may be 70 adjusted. Since the bight of the yoke 22 is pivotally connected to the arm 3 it is apparent that the yoke may be adjusted so as to hold the arm 3 in different adjusted positions.

In operation the toe block 8 is engaged in the toe of the shoe and the heel member 19 with the heel thereof, whereupon rocking of the lever 11 will force the member 19 rearwardly, thereby firmly holding the shoe since 85 the pawl will engage a selected ratchet tooth. By providing the notches 10 the lever may be adjusted quickly for shoes which vary greatly in sizes.

In Fig. 4 of the drawing the holder is 90 shown reversed so that shoes may be polished or cleaned when inverted.

From the foregoing description it will be seen that a holder has been provided so constructed that the same can be easily and 95 quickly taken apart for packing, and one which may be used by shoe merchants for holding the shoes when changing the buttons.

To rotatably connect the block 1 to the 100 block 1', a screw 24 is attached thereto and passes through the block 1, and has its extended end engaged by a winged nut 25, which is operable to clamp the block 1 tightly against the block 1'. When it is 105 desired to reverse the holder, it is only neces-

sary to turn the winged nut, whereupon the block 1 can be rotated, thus positioning the holder, as shown in Fig. 4.

What is claimed is:—

5. 1. A shoe holding device comprising a supporting block, an arm pivotally connected thereto, a loop pivotally connected to the arm and adjustably connected to the block, a toe block carried by the arm, a lever slidably and pivotally connected to the arm, means carried by the lever for engaging the arm to hold said lever in different adjusted positions, and a heel engaging member carried by the lower end of said lever.
10. 2. A shoe holding device comprising a supporting block, an arm pivotally connected at its rear end to the supporting block, a yoke having its bight pivotally connected to the arm, said yoke having its arms detach-

ably and adjustably engaged with the block, 20 a toe member carried by the outer end of the arm, a lever having a longitudinal slot formed therein for slidably engaging the arm, a pawl having one end pivotally connected to the lever, said arm having ratchet 25 teeth formed thereon for engagement with the pawl, notches formed in said arm, a pin bridging the slot of the lever for interchangeably engaging said notches, and a heel engaging member removably connected 30 to the lower end of the lever.

In testimony whereof, I affix my signature, in the presence of two witnesses.

JOHN H. PLANK.
